UNITED STATES PATENT OFFICE.

BENNO SCHUBART, OF NUERMBERG, GERMANY, ASSIGNOR TO VEREINIGTE SCHUHFABRIKEN BERNEIS WESSELS AKTIENGESELLSCHAFT, OF AUGSBURG-OBERHAUSEN, GERMANY.

DESIGN FOR A TOY AMUSEMENT BOX.

Application filed July 30, 1928, Serial No. 27,621, and in Germany April 11, 1928. Term of patent 3½ years.

To all whom it may concern:

Be it known that I, BENNO SCHUBART, a citizen of the German Republic, residing at Nuremberg, Germany, have invented a new, original, and ornamental Design for a Toy Amusement Box, of which the following is a specification, reference being had to the accompanying drawing, forming part thereof. The figure is a perspective view of a toy amusement box showing my new design.

I claim:

The ornamental design for a toy amusement box as shown.
